UNITED STATES PATENT OFFICE.

FRANK SAWFORD, OF VANCOUVER, BRITISH COLUMBIA, CANADA.

COAL PULVERIZER.

Application filed June 12, 1923. Serial No. 644,942.

To all whom it may concern:

Be it known that I, FRANK SAWFORD, citizen of the Dominion of Canada, residing at Vancouver, in the Province of British Columbia, Canada, have invented certain new and useful Improvements in Coal Pulverizers, of which the following is a specification.

This invention relates to a system of pulverizing coal and for delivering it to a furnace for combustion with the air by which the pulverized coal is separated.

The full advantages derivable from the use of pulverized coal as a fuel are not at present attained, as the cost of drying, pulverizing and sifting the coal dust to the required degree of fineness involves, as at present practised, a capital outlay that is prohibitive in any except large installation.

In the invention, which is the subject of this application, the fuel is pulverized, not by crushing, but by impact with beaters revolving at a high velocity, and the separation of the coal dust when sufficiently fine is effected, not by screening, but by a draught of air, which air is used as the medium of conveyance of the coal dust to the furnace and is there consumed with it with such further supply of air as may be necessary or desired.

Means is also provided for retaining the fuel exposed to the beaters until it is sufficiently fine to be carried away in the air draught, and for regulating the amount of air, either hot or cold, delivered with the fuel to the furnace and the amount of that air drawn through the pulverizer whereby the fineness of the coal dust is regulated.

This elimination of the requirements for crushing and screening dispenses with the need for drying the coal, which drying is more particularly necessary when the coal is to be crushed and screened, because even a small amount of moisture in the coal is a hindrance in that work but it not objectionable in combustion.

The impact pulverizer and the air fan by which the separation of the coal dust is effected, and the means by which the coal is fed to the pulverizer and the coal dust delivered to the furnace for combustion with the air in which it is carried in suspension all constitute a self-contained machine of small size and simple design and one which performs its work in an eminently satisfactory manner.

The invention is fully described in the following specification, reference being made to the drawings by which it is accompanied, in which:

Fig. 1 is a vertical longitudinal section.

Figs. 2, 3, 4 and 5 are enlarged details illustrating the lining ring of the pulverizer.

Fig. 6 is a detail of the pulverizing wheel, a part being in section to show the preferred manner of securing the radial pin.

Fig. 7 is a cross section of the pulverizer on the line 7—7 in Fig. 1 looking in the direction of the arrow.

Fig. 8 is an end elevation of the centrifugal fan and its casing removed from the pedestal support, and

Fig. 9 shows the means for driving the coal feed from the pulverizer shaft and of connecting the air control dampers to the coal feed control.

In these drawings 2 represents the base of the machine on which are secured hollow pedestals 3 and 4 which carry the bearings of the shaft 5 on which the pulverizer and its air fan are secured and between which pedestals the casing 6 of the pulverizer and 7 of the fan are secured.

The pulverizer casing 6 is conically reduced toward each end from an intermediate cylindrical portion adapted to receive a lining of hard metal pulverizing rings 8, the casing and rings being diametrically halved and jointed together in a horizontal plane. Each ring 8 has an inwardly projecting ridge 9, the inner surface of which is deeply corrugated, as shown in Fig. 2, and the sides of the ridges 9 are correspondingly corrugated to a less depth as shown in Fig. 5, the circumferential and lateral corrugations merging into one another.

In the spaces between the ridges 9 of these rings pass the pins 10 of wheels 11, which pins are secured in the wheels to radially project from their outer edges. Preferably the pins 10 are formed in pairs, each pair being bent from one piece of round rod and the bend is cast in the wheel, as shown in Fig. 6.

A number of these wheels 11 with their radially projecting pins 10 are keyed together on the shaft 5 and at each end of the group is secured an open spoked wheel 13 having a rim which is coned to conform to the corresponding part of the casing 6.

A hollow, cylindrical bushing 15 is secured to the face of the pedestal 3 to pro-

ject within it concentric with the shaft 5 and leave an annular space 16 surrounding the shaft. Into the upper side of this bushing 15 projects the lower end of a chute 17 through which the coal to be pulverized is delivered from a feed screw 18 rotatably mounted in the lower end of a hopper 19 secured to the upper side of the pedestal 3 and supported on the upper side of the pulverizer casing 6.

The fan casing 7, which is in direct communication with the space within the pulverizer, is mounted between a circular flange on the pulverizer casing and a corresponding flange on the pedestal 4 with the cavity of which the casing 7 is also in direct communication. Being mounted on two circular flanges, enables the discharge 20 of the fan to be turned to any desired position or 20 angle around the shaft 5 that may be found convenient for connection to the furnace.

The wall of the pedestal 3 has an aperture 21 through which a supply of external air may be admitted to pass through the pulverizer with the coal, which air supply is controlled by a damper 22. Similarly an aperture 23 is provided in the other pedestal 4 through which a supplementary supply of external air may be admitted and controlled by a damper 24 to regulate the draught of the fan 12 through the pulverizer, and the amount of air delivered with the fuel to the furnace.

The cavities of the pedestals 3 and 4 are 35 not only in communication with the pulverizer casing and the fan casing respectively, but are connected to the space within the base 2, to which space air is supplied which has been heated in any convenient manner 40 by the waste heat from the furnace. Preferably the base 2 is secured on a hot air flue F with which it is in communication, as shown in Fig. 1.

Dampers 26 and 27 are slidable across the 45 apertures between the base 2 and the pedestals 3 and 4 by which dampers the amount of heated air admitted to the pulverizer and the fan may be regulated to what is required.

The shaft 5 on which is secured the fan 50 12, the pulverizing wheels 11 and the conical rimmed wheels 13, is driven at a suitable speed of rotation from any convenient source of power, either as shown by a belt over a pulley 25 and the coal feed screw 18 is rotated at a relatively low speed of rotation by any convenient means from the shaft 5 that will afford facility for regulating the amount of coal delivered to the pulverizer.

In the drawing it is shown as operated by 60 a pawl 30 on the end of a radius arm 31 mounted to move freely on the shaft 28 of the feed screw 18 and engage the teeth of a ratchet wheel 29 secured on the same screw shaft to rotate with it. The pawl lever 31 65 is oscillated through a definite arc of move-

ment by a rod 32 from the pin of a crank disc which is rotated by worm gear at 34 and 35 from the pulverizer shaft 5.

An arm 36 is mounted on the shaft 28 of the feed screw, which arm has an arcuate portion 37, concentric with and projecting across the toothed edge of the ratchet wheel 29, which, as moved to or from the pawl 30, will determine the number of teeth engaged by the pawl.

This lever 36 and arcuate shield 37 may be moved by a rod 42 to control the coal feed, either by hand or automatically, by the steam pressure of the boiler or by the temperature of the gases as delivered from the furnace or to the smokestack.

The dampers 22, 24 may be adjustably connected by rods 38, 41 to the control arm 37 of the coal feed mechanism that the amount of air admitted may be varied with 85 the amount of coal fed to the pulverizer.

The coal to be pulverized, previously broken to a suitable size, is continuously fed from the hopper 19 and delivered through the chute 17 into the space 16 within the 90 cylindrical bushing 15 and passes therefrom through the conical wheel 13 at that end of the pulverizer. As it passes through the wheel 13 it is thrown violently outward by centrifugal force into the space between the 95 lining rings 8 and the wheels 11, which space is swept by the pins 10 projecting from the wheels.

Through this space it is carried by the draught from the fan 12 and is effectively 100 broken into a fine powder, as the centrifugal tendency throws it into the spaces between the ridges 9 of the rings which spaces are more closely swept by the ends of the pins 10.

As soon as the coal is pulverized to a degree of fineness that it is held in suspension in the air, the draught of the fan draws it with the air and delivers it through the fan discharge 20 for delivery to the furnace.

Particular attention is drawn to the important part played by the oppositely coned wheels 13. The arms of these wheels have a blade area little, if any, inferior to that of the fan blades and they travel at the same 115 velocity, so that they exercise a considerable centrifugal effect on the air with which they come in contact. The rims of these wheels 13 being oppositely coned to direct the air delivered from them into the pulverizer, their effect will be to counteract one another and retain the coal within the scope of the beaters until it is sufficiently fine to be carried away by the preponderating draught due to the fan 12.

The dampers 22 and 26 afford full control of the amount of air delivered with the fuel to the pulverizer and the temperature of the air so admitted and the dampers 24 and 27 control not only the amount of air to be 130

delivered with the fuel to the furnace and its temperature, but regulate the draught through the pulverizer and therefore the degree of fineness to which the fuel is reduced, 5 and these air controls may be co-operative with the fuel control.

It must be noted that the pulverizing is effected by the impact of the arms of the wheel 13, and the radially projecting pins 10 on the coal, and by the coal against the corrugations of the lining rings 8, and not in any way by direct crushing.

It must be distinctly understood that the flow of air by which the pulverized fuel is 15 separated from that not sufficiently pulverized may supply sufficient air to satisfy the requirements of combustion, but if not a further supply of air may be furnished at or adjacent the delivery of the pulverized fuel 20 and air to the furnace.

I do not desire to be confined to the particular arrangement and construction of the parts as described and illustrated, as the structural features may be varied within 25 wide limits without departing from my invention: Thus, while the drawing shows a number of lining rings and a corresponding series of pinned wheels rotatable in proximity to them, it is believed that this number 30 may be considerably reduced without impairing the efficiency of the machine as a pulverizer.

A considerable proportion of the energy applied to effect the pulverization naturally 35 causes an increase in temperature of the air within the pulverizer, which together with the heated air admitted through the dampers 26 is sufficient to evaporate the moisture from the coal, and as the coal and air are 40 delivered direct to the furnace the energy so spent is not wasted.

Having now particularly described my invention, I hereby declare that what I claim as new and desire to be protected in by 45 Letters Patent, is:

1. A means for pulverizing coal or the like material and for delivering it for combustion, said means comprising a rotatable body having projections on its periphery, a 50 spoked wheel at each end of the rotatable body and rotatable with it, each wheel having a rim which is conically reduced from approximately the diameter of the rotatable body and its projections, a casing enclosing 55 the rotatable body and conforming closely to the space swept by its projections and the conical rims of the wheels rotatable with it said casing having projections interspaced with those of the rotatable body, 60 means for delivering the coal to be pulverized within the conical rim of the wheel at one end of the rotatable body, means for delivering a controlled supply of air with the coal, means for withdrawing from the other 65 end of the casing the air with such coal dust

as is held in suspension with it and for delivering it outside of said casing, and means for varying the draught of air through the casing.

2. A means for pulverizing coal or the like material and for delivering it for combustion, said means comprising a series of disc wheels secured on a rotatable shaft with the disc surfaces a short distance apart, said discs having pins radially projecting from 70 their periphery, a spoked wheel secured at each end of the series of discs to rotate with them, each wheel having a rim which is conically reduced from the pins of the discs, a casing conforming closely to the sweep of 75 the pins of the discs and the conically rimmed wheels rotatable with them, said casing having rings projecting between the pins of each disc, the inner and side surfaces of each ring being corrugated, means for 80 feeding the coal to be pulverized within one of the conical rimmed wheels, means for delivering a supply of air to the same, means for withdrawing the air with such of the coal as is held in suspension with it through 85 the other end of the casing and for delivering it outside of said casing, and means for varying the draught of air so withdrawn.

3. A means for pulverizing coal or the like material and for delivering it for combustion, said means comprising a rotatable body having pins radially projecting from 90 its outer surface, said pins being bent to a U-shape with the bend cast in the body, a casing conforming closely to the sweep of 95 the projections and having projections interspaced between those of the rotatable body, means for delivering the coal to be pulverized within one end of the casing, means for admitting air to the same end of 100 the casing, means for withdrawing the air from the other end of the casing with such of the pulverized coal as is held in suspension with it and for delivering it outside of 105 said casing.

4. A means for pulverizing coal or the like material and for delivering it for combustion, said means comprising a series of disc wheels secured on a shaft, each wheel having pins radially projecting from its periphery, the pins being bent to a U-shape with the bend cast in the rim of the wheel, a spoked wheel secured on the same shaft at each end of the series of discs, each wheel having a conical rim the larger end of 110 which extends from adjacent the outer ends of the pins, a casing having a cylindrical portion around the disc wheels, and conically reduced therefrom to conform closely to the conical rims of the spoked wheels, a series of rings fitted within the cylindrical portion of the casing, each ring projecting inward between the pins of the several discs, the inwardly projecting portion of each ring being corrugated around its inner circum- 115 120 125 130

ference and around its sides, means for delivering the coal to be pulverized within the smaller end of one of the conical rimmed wheels, means for supplying air to the same end, means for withdrawing the air from the other end of the casing with such of the pulverized coal as is held in suspension with it and for delivering it outside of said casing, and means for varying the draught of the air so withdrawn.

5. A means for pulverizing coal or the like material and for delivering it for combustion, said means comprising a rotatable body having projections from its periphery, a casing closely conforming to the space swept by the projections of the rotatable body, means co-operative with rotation of the body for delivering the coal to be pulverized into one end of the casing, means for varying while the machine is running the amount of coal so delivered, means for delivering a supply of air to the same end of the casing, means co-operative with variation of the coal feed for varying the amount of air so admitted, and means for withdrawing the air from the casing with such of the coal dust only as is held in suspension with it, and for delivering it with the coal dust for combustion.

10. 6. A means for pulverizing coal and for delivering it with air for combustion, said means comprising a series of disc wheels secured on a rotatable shaft with their disc surfaces a short distance apart, each wheel having pins radially projecting from its periphery, a spoked wheel secured on the same shaft adjacent each end disc of the series, each spoked wheel having a rim which is conically reduced from approximately the diameter swept by the pins of the discs, a casing enclosing the discs and the conically rimmed wheels and conforming closely to the space swept by them, said casing having rims projecting into the spaces between the pins of adjacent discs the inner surfaces and sides of said rings being corrugated, means co-operative with rotation of the shaft for feeding the coal to be pulverized within the smaller diameter of one of the conically rimmed wheels, means for regulating the amount of coal feed, means for admitting a supply of heated air with the coal to be pulverized, means for admitting a supply of external air to the same, means co-operative with the coal feed for varying the amount of

air admitted; a fan exhausting the air and the coal dust carried in suspension with it from the pulverizer and for delivering it for combustion, means for admitting a controlled supply of heated air to the fan adjacent the connection of the fan to the pulverizer, and means for admitting a controlled supply of external air to the same whereby the draught of air through the pulverizer may be varied.

7. In a coal pulverizing machine, means for pulverizing coal, means for admitting air into the pulverizing means, means for withdrawing the pulverized coal and air from the pulverizing means and delivering it outside of the apparatus, means for automatically controlling the amount of coal fed to the pulverizer and means for simultaneously controlling the amount of air permitted to pass through the pulverizer, substantially as shown and described.

8. In coal pulverizer, means for pulverizing the coal, means for passing an air stream through said pulverizing means to cause the coal dust to pass with air stream out of the pulverizer, means for controlling the amount of coal fed to the pulverizer, means for controlling the amount of air admitted to the pulverizer to constitute the air stream that passes through the pulverizer, and means for automatically actuating said coal controlling means and said air admission controlling means in co-operation.

9. A mechanism for pulverizing coal or the like and delivering it for combustion, said mechanism comprising a rotatable pulverizer body having projections on its periphery, a casing closely conforming to the space swept by the projections of the rotatable body, said casing having an inlet at one end and an outlet at the other end, means for admitting fuel into the inlet end of said casing, a suction fan connected with the outlet end of said casing for creating a suction from the inlet to the outlet end of said casing and delivering the air and finely divided coal from the fan outlet, means for admitting air to the inlet end of the casing, an independent means for admitting air to the suction fan and automatically controlled dampers for said air admitting means co-operative with the fuel supply substantially as shown and described.

In testimony whereof I affix my signature.
FRANK SAWFORD.
